US00D747259S

(12) **United States Design Patent**
Scooler et al.

(10) **Patent No.:** US D747,259 S
(45) **Date of Patent:** ** Jan. 12, 2016

(54) **PAIR OF AIRCRAFT WINGS**

(71) Applicant: **Gulfstream Aerospace Corporation**,
Savannah, GA (US)

(72) Inventors: **James Scooler**, Savannah, GA (US);
Angel Barboza, Savannah, GA (US);
Guilherme Oliveria, Savannah, GA
(US); **Andre Martins**, Savannah, GA
(US)

(73) Assignee: **Gulfstream Aerospace Corporation**,
Savannah, GA (US)

(**) Term: **14 Years**

(21) Appl. No.: **29/506,143**

(22) Filed: **Oct. 13, 2014**

(51) LOC (10) Cl. **12-07**

(52) U.S. Cl.
USPC **D12/345**

(57) **CLAIM**

The ornamental design for a pair of aircraft wings, as shown
and described.

DESCRIPTION

FIG. 1 is a front perspective view of a pair of aircraft wings
showing our new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines illustrate environment and structure that
form no part of the claimed design.

1 Claim, 5 Drawing Sheets
